Primary Examiner — Manpreet S Matharu*Assistant Examiner* — J. Thorn, Sr.*(74) Attorney, Agent, or Firm* — Kaplan Breyer Schwarz, LLP(57) **CLAIM**

The ornamental design for an inner filter element, as shown and described.

DESCRIPTION

FIG. 1 is a top front right perspective view of the inner filter element showing the new design;

FIG. 2 is a bottom rear left perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The portions shown in the figures in broken lines do not constitute part of the claimed design.
